ANCHOR INSERT

Arthur M. Kinninger, Dayton, Ohio, assignor of
one-half to Carl A. Kinninger, Dayton, Ohio

Application February 6, 1932, Serial No. 591,348

18 Claims. (Cl. 72—101)

My invention relates to concrete building constructions, and more particularly to a channel insert to be initially positioned within a concrete form for embedment in the concrete structure to 5 form an anchor slot therein, and tie members engageable therewith for anchoring to the structure a masonry veneer or facing of brick, stone or terra cotta and the like.

The present invention includes a channel 10 shaped form member of comparatively thin material having a contracted or restricted slot like orifice with which are associated means for securing the channel form to the interior of a concrete form structure and spreader means for reinforcing the channel insert to enable it to withstand the pressure of the deposited concrete together with coupling means for interconnecting succeeding sections or lengths of insert channels in longitudinal alignment with each other and 20 for closing the terminal ends of such insert to prevent the entrance of plastic concrete. There are also associated with such channel inserts, anchor ties which are reversible, either end thereof being engageable in the anchor slot formed by 25 such channel member, and the other end embedded in the mortar joints of the masonry facing.

The object of the invention is to simplify the construction as well as the means and mode of 30 application of such channel inserts, whereby they will not only be cheapened in construction, but will be more efficient in use, capable of being easily and quickly applied to concrete form structures, of increased strength and durability, and 35 unlikely to get out of repair.

A further object of the invention is to provide economical means for attaching the insert channels to the interior of a concrete form structure, and for bracing the side walls of the channel inserts to enable them to resist the pressure of surrounding concrete deposits.

A further object of the invention is the duo-functional use of a commercial staple as an attachment and spreader means for the channel 45 inserts.

A further object of the invention is to provide improved coupling means for aligning succeeding sections of the insert channel with each other, and for engaging such coupling means therewith.

50 A further object of the invention is to provide improved closure means for the terminal ends of the channel inserts to prevent the entrance of plastic concrete thereinto.

A further object of the invention is to provide a 55 duo-functional closure and coupling member for

the concrete sections and to provide simple and economical means for detachably connecting such member therewith.

A further object of the invention is to provide an improved form of reversible anchor tie engageable within the embedded channel inserts, the opposite ends of which are adapted for engagement therewith, whereby in whichever position the workmen may pick up the anchor tie, it will be properly positioned for easy engagement 10 with the inserts.

A further object of the invention is to facilitate the manufacture and mode of assembly of such construction.

With the above primary and other incidental 15 objects in view, as will more fully appear in the specification, the invention consists of the features of construction, the parts and combinations thereof, and the mode of operation, or their equivalents, as hereinafter described and set forth 20 in the claims.

Referring to the accompanying drawing, wherein is shown the preferred, but obviously not necessarily the only form of the embodiment of the invention, Fig. 1 is a perspective view 25 of a portion of a concrete body, and the form therefor partially stripped away from the concrete body to disclose a channel insert, forming a part of the present invention, embedded therein.

Fig. 2 is a perspective view showing a portion of a building structure embodying the present anchor slot insert and the anchor tie engaged therewith. Fig. 3 is a perspective view of an assembled aligned anchor slot insert showing a duo-functional closure and coupling member 30

engaged with one end portion, and illustrating the relation of the duo-functional spreader and attachment staples. Fig. 4 is a detail perspective view of the closure and coupling member detached from the anchor slot insert, and the end 40

of the insert adapted to receive the closure and coupling member. Fig. 5 illustrates several forms of anchor ties interchangeably engageable with the anchor slot inserts, all of which may be employed in the same building structure. 45

Fig. 6 is a detail view of a modification of the spreader and attachment means. Fig. 7 is a modification wherein the legs of the attachment extend exteriorly of the channel side walls. Fig. 8 is a transverse section viewed from the bottom 50

of Fig. 6.

Like parts are indicated by similar characters of reference throughout the several views.

Referring to the drawing, 1 indicates a portion of a concrete structure, and 2 the wooden 55

form within which the concrete body 1 was deposited and to the interior of which the anchor slot insert channel, forming the subject matter hereof, was initially attached for embedment in 5 the concrete body. Such anchor slot insert comprises a channel 3, preferably of sheet metal but which may be of other sheet material, the side walls of which approach each other to afford a restricted longitudinal slot like orifice 4. In the 10 present instance the side walls of the channel are shown convergent or oppositely flaring throughout a portion of their extent as at 5 and substantially parallel throughout the remainder of their extent as at 6, the flaring and parallel 15 portions being joined by a lateral offset or shoulder 7. While this construction is preferable and desirable, it is not essential and the shape of the channel may be varied to meet different conditions of use and in accordance with the desires and preference of different building constructors. 20 However the form illustrated in the drawing has been found to be quite efficient and desirable as well as economical in manufacture. The channel insert is preferably, though not necessarily, 25 provided with outwardly extending marginal flanges 8 to afford a contact bearing with the interior base of the form wall to which the insert is initially attached.

By providing spacers or reinforcing members 30 at intervals throughout the length of the anchor slot insert, such as wooden blocks or diaphragm plates 9 which conform to the shape of the channel, relatively light material may be employed. The spacer plates 9 may be made from sheet 35 metal and be provided with marginal ears or tongues 10 projecting perpendicular to the plane of the spacer plates 9 and having bearing upon the interior walls of the channel to properly position the spacer plates therewithin. If so desired the walls of the channel inserts may be 40 embossed to provide projections or bosses 11 within which are seated corresponding bosses 12 upon the tongues of the spacer plates 9. If the bosses or projections 11 are inwardly directed, 45 the tongues 10, of the spacer plates, may be perforated to engage therewith to thereby hold the spacers in properly spaced relation with each other. In the event that wood blocks or the spacer plates 9 are employed, ordinary nails may 50 be driven through perforations in the channel into the concrete form 2 for temporarily supporting the channel inserts in position to be embedded in the concrete mounting.

However, the preferable method of temporarily 55 attaching the insert channels to the interior base of a concrete form, is by use of ordinary commercial staples 14 of a size corresponding substantially to the width of the slot like orifice 4 of the channels. Such staples 14 duo-functionally serve to secure the channels to the concrete 60 forms and also act as spacers to hold the side wall above the channels in properly spaced relation and reinforce the channel walls to resist the pressure of the concrete deposited thereabout. 65 Such staples 14 are driven through spaced perforations in the wall of the channel and extend thence through the channel insert with their points projecting through the orifice slot 4 in position to be driven into the wall of the concrete 70 form 2 as illustrated in Fig. 1. When so driven into the form the legs of the staple 14 rigidly resist any contractive movement of the insert channel. Such construction is not only convenient and economical, but it affords an extremely rigid reinforcement for the insert chan-

nel enabling the use of comparatively light weight and hence inexpensive material.

To prevent the inflow of the plastic concrete to the interior of the insert channels and also to insure proper longitudinal alignment of succeeding sections of such channel inserts, terminal closures 15 are provided. These closures 15 are shaped to substantially agree with the cross sectional contour of the insert channel and are provided with marginal ears or tongues 16 and 17 turned in opposite directions into substantially perpendicular relation with the closures 15. The ears or tongues 16 extend exteriorly of the parallel portion 6 of the channel walls and are perforated for engagement over bosses or projections 18 formed in such wall portions. By squeezing or flexing the channel walls, the closure is easily engaged and disengaged with such projections or bosses 18 to securely and rigidly hold the closure member in position. The ears or tongues 16 are proportioned to fit between offsets or shoulders 7 and the out-turned marginal flanges 8, of the channel, which thus assist in holding the closure immovably upon the channel insert. The oppositely turned tongues or ears 17, carried by the closure member 15, form a receiving socket for locating the terminal end of the next succeeding section of insert channel in accurate alignment with the preceding section. The ears or tongues 17 extend exteriorly of the end of the adjacent insert channel portion. Thus the members 15 duo-functionally serve to couple and align the succeeding sections of the anchor slot channel, and at the extremities of such inserts may serve to close the channel to 35 exclude plastic concrete, dirt or other material.

The anchor ties for use with the insert channels, may be of various forms, several of which are illustrated in Fig. 5. Such anchor ties are preferably, though not necessarily, stamped from 40 sheet metal of somewhat heavier gage than that from which the insert channels are formed. The anchor ties 19 are formed with terminal heads 20 agreeing with the interior contour of the insert channels with which the ties are engaged by 45 inserting the heads 20 into the channel through the slotted orifice 4, and giving to the tie a partial rotation into a transverse plane wherein the enlarged head 20 will have interlocking engagement within the channel. The head 20 of the 50 anchor tie is shown provided with right angle shoulders or offsets 21 which seat upon the shoulders or offsets 7, of the channel, while the divergent or beveled margins of the head 20 have seating engagement upon the flaring portion 5 of 55 the channel. When employed for attaching stone masonry to the face of a concrete structure, the anchor ties are bent at right angles, at their outer extremities as at 22, for engagement in a suitably positioned hole in the facing 60 stone. Ordinarily, however, these anchor ties are embedded in the mortar joints between succeeding bricks, stones or blocks or terra cotta. To afford the necessary anchorage, the tie is perforated as at 23 and may be formed with marginal projections, lugs, or ears 24, which become embedded in the mortar joints thereby serving to securely anchor the masonry to the concrete 65 structure within which the insert channel is embedded. The preferred form of anchor tie for 70 ordinary use is that shown at 25 upon which identical heads 20 are formed at the opposite terminals of the anchor tie whereby the tie is reversible. Thus in whatever position the tie may be picked up by the workmen, that is with 75

either side uppermost and either end foremost it is ready to be quickly and easily interlocked within the embedded insert channel. In such case one end of the tie has the interlocking engagement with the interior of the channel walls by being partially rotated into a transverse plane after insertion through the orifice slot 4, while the opposite head 20 affords further and additional interlocking engagement with the mortar joints in which it is embedded.

While the insert channels may be manufactured in any suitable length for ordinary commercial production, they are manufactured in lengths of four feet each, each such section being perforated at three spaced intervals to receive the attaching and reinforcing staples 14. In assembling the channel forms upon the interior of the concrete form structure they are secured end to end by driving the staples 14 into the wall of the structure, the succeeding sections being held in properly aligned relation by the closure and coupling members 15 interposed therebetween. In the event that staples are not employed for attaching the slot liner channel to the interior of the concrete form, spacer heads or diaphragms 9 distributed throughout the length of the liner channel at spaced intervals may be substantially identical with the terminal heads or closures 15, but of slightly smaller size whereby such spacer heads may be inserted within the channel as shown in Fig. 6 wherein the oppositely extending tongues or ears 10 will prevent the reinforcement heads assuming an inclined or askew position. Such reinforcement heads may be detachably engaged with the slot liner or channel in a manner quite similar to the interengagement of the terminal heads therewith, that is by means of the perforations 11 engaging over bosses or projections 12 in the side walls of the liner channel.

The terminal heads 20 of the anchor ties substantially conform to the flaring or convergent portions of the side walls of the channel or liner, and such anchor ties have neck portions adjacent to the flaring heads 20 which agree in width with the space between the parallel portion 6 of the slot liner or channel. Such neck portion of the tie, by its engagement with the interior substantially parallel surfaces of the portions 6—6 of the channel, hold the anchor tie against wobble movement and maintain succeeding anchor ties engaged with the slot liner channel in parallel alignment with each other. A slight right angle shoulder or offset 21, adjacent to the flaring head 20, is preferably, though not necessarily, provided upon the anchor tie members for seating engagement with the shoulder or offset 1 of the channel member.

In Fig. 7 there is shown a modification wherein in a short spacer 22 which may be a short wire or rod, but which for economy is preferably a small nail or wood block is interposed between the portions 6 of the side walls where its ends seat within the sockets formed by outwardly extending bosses or projections 18 formed in the wall portions 6 at spaced intervals throughout the length of the insert. Such spacer resists contraction of the insert channel under pressure of the deposited concrete and maintains the slot 4 of proper width. This form of spacer is alternative to the use of a staple, as shown in Fig. 3, or the spacer head 9, shown in Fig. 6.

As a further modification of the spacer and attachment means, there is shown in Fig. 8 a staple 14' of greater width than the staple 14 pro-

jected through aligned holes in the side walls 5 and flanges 8 of the channel and engageable with the form board. The legs of the staple 14' extend exteriorly of the portions 6 of the side walls and not only reinforce the channel against collapse, but also hold it against spreading. The staple 14' like the staple 14 not only serves as an attachment means but also reinforces the channel to enable it to resist the pressure of the concrete.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. In a slot-forming unit for a concrete form, a channel-shaped body and a staple extending transversely through the channel and projecting from the open side thereof for securing the channel to the form wall, the legs of the staple serving as spacers to limit the approach of the side walls of the channel toward each other.

2. In a slot form for a concrete form, the combination with a channel-shaped body, of a fastening device having securing engagement with a supporting form structure for securing the channel-shaped body thereto and having portions simultaneously engaging the opposite side walls of the channel to limit approach of the latter toward each other.

3. The combination with a channel-shaped body, of a staple projecting through the wall of the channel and into a supporting structure with its legs extending in proximate relation with the sides thereof to limit the approach of the walls relative to each other, and attaching the channel to a support.

4. The combination with a yielding channel-shaped body, of a duofunctional spacer and attachment means transfixing the channel-shaped body and accessible from the exterior thereof including a portion simultaneously engaging the opposite side walls of the channel-shaped body for relatively spacing the side walls of the channel in relatively fixed spaced relation, and a sharpened portion to be driven into a support for attaching the channel to the support.

5. A slot-forming unit for a concrete form including a flexible channel-shaped body, and a staple piercing the channel-shaped body and thence engaging in the wall of a concrete form for attaching the channel to the form wall, the legs of the staple having engagement with the channel walls to maintain them in spaced relation with each other.

6. A slot-forming unit for a concrete form including a channel-shaped body, a driven member for securing the channel to a form wall, positively engaging both the channel-shaped body and the

form wall and having spacing engagement with the side walls of the channel to maintain them in spaced relation with each other.

7. A slot-forming unit for a concrete form including a channel-shaped body, and a closure head for the end of the channel including means for aligning a second channel-shaped body with the first body.

8. A slot-forming unit for a concrete form including a channel-shaped body, a duofunctional closure head for the end of the channel body to close the channel to exclude plastic concrete and locating means upon the exterior side of said closure head for receiving the end of a like channel-shaped body to also align a second channel-shaped body with the first mentioned body.

9. The combination with a channel-shaped body of a terminal closure head therefor conforming to the transverse contour of the channel-shaped body and oppositely extending marginal flange portions carried by the closure head for simultaneous engagement with consecutive channel-shaped bodies.

10. The combination with consecutively, aligned channel-shaped bodies of a transversely arranged closure head interposed therebetween and common to both sections, and means for interengaging such head with the respective sections.

11. A slot-forming unit for a concrete form including a channel-shaped body to be attached to the interior of a concrete form, a closure for the end of the channel and spacer means intermediate the ends of the channel for maintaining the side walls thereof in predetermined spaced relation.

12. A slot-forming unit for a concrete form, including a channel-shaped body of sheet material, the side walls of which are divergent throughout a portion of their width and substantially parallel throughout the remainder of their width, and substantially right angle stop shoulders interposed between the substantially parallel portions of the divergent portions of such walls.

13. A slot-forming unit for a concrete form including a channel-shaped body of sheet material having inwardly directed side walls, adapted to be embedded in a body of concrete with its open side exposed in the face of the concrete body, and a reversible anchor tie including similarly enlarged head portions at each end of the tie engageable within the channel-shaped body, whereby either end of the anchor tie may be engaged with the channel.

14. An anchor slot liner comprising a channel of sheet material to be embedded in a body of concrete with its open side exposed, including angularly converging side wall portions affording an open side of reduced width, and contiguous, substantially parallel portions extending in substantially parallel spaced relation, and anchor tie members, enlarged bearing portions upon the tie members engageable within the channel with the converging side wall portions and a contiguous straight portion upon the anchor tie members engageable with the spaced parallel portions of the channel side walls to maintain parallel alignment of succeeding anchor ties and prevent wobbling.

15. A slot forming insert for a concrete body including a yielding channel shaped form of sheet material, means for attaching the channel to the interior of a concrete form wall, seating areas formed on the opposite walls of the channel shaped form, and spacer members disposed transversely of the channel and having engagement with said seating areas to reinforce the channel against external pressure.

16. The combination with a channel-shaped body, of spacer means including a portion disposed interiorly of the channel simultaneously engaging the side walls thereof limiting the approach of its side walls one toward the other, and a pointed portion for transfixing the channel-shaped body and for securing the channel to the side wall of a concrete form into which the element is driven.

17. A slot-forming unit for a concrete form including a channel-shaped body, a closure head for the end of the channel-shaped body, one of said members being resilient, corresponding registering embossed areas on the closure head and channel respectively, having interlocking seating engagement one in the other and means for detachably interlocking the closure head with the channel-shaped body under the inherent tension of the resilient member.

18. In a slot-forming unit for a concrete form, the combination with a resilient channel-shaped body to be secured interiorly of the form, and a closure head therefor of registering indentations upon both the channel and head, having interlocking seating engagement one within the other and held in engagement by the resiliency of the channel.

ARTHUR M. KINNINGER.
